(57) **CLAIM**

The ornamental design for a fluid delivery device body portion, as shown and described.

DESCRIPTION

FIG. 1 is a left side perspective view of a fluid delivery device body portion showing my new design;

FIG. 2 is a right side perspective view showing the design for the fluid delivery device body portion of FIG. 1;

FIG. 3 is a front elevational view showing the design for the fluid delivery device body portion of FIG. 1;

FIG. 4 is a rear elevational view showing the design for the fluid delivery device body portion of FIG. 1;

FIG. 5 is a left side elevational view showing the design for the fluid delivery device body portion of FIG. 1;

FIG. 6 is a right side elevational view showing the design for the fluid delivery device body portion of FIG. 1;

FIG. 7 is a top plan view showing the design for the fluid delivery device body portion of FIG. 1; and,

FIG. 8 is a bottom plan view showing the design for the fluid delivery device body portion of FIG. 1.

The broken lines shown in the drawings illustrate portions of the fluid delivery device body portion that form no part of the claimed design.
